ROTARY BIT

James L. Montgomery, Arthur J. Tarbell, and
Emmett H. Irwin, Long Beach, Calif.Application December 22, 1930
Serial No. 503,864

4 Claims. (Cl. 255—71)

This invention relates to a rotary bit particularly applicable for the drilling of oil wells, and the prime object is to provide a bit of the disc type in which both of the discs are so interconnected that they rotate in unison.

Another object is to provide a bit of the character stated in which neither of the discs can wear flat due to constant wear in one position.

Still another object is to provide a bit which 10 is self-cleaning, and which will not become choked and clogged with material and cuttings while in the hole.

Other objects, advantages, and features of invention may appear from the accompanying 15 drawing, the subjoined detailed description, and the appended claims.

In the drawing

Figure 1 is a side elevation of our bit.

Figure 2 is a face view of one of the discs.

20 Figure 3 is a face view of a plane disc which may be used in our bit.

Figure 4 is a bottom plan view of our bit.

Referring more particularly to the drawing, the numeral 1 indicates the shank of our bit 25 which is secured to the bottom of the drill pipe in the usual manner. That is, by screwing the drill pipe on to the threaded pin 2. A pair of arms 3—4 depend from the bottom of the shank 1 and a disc 5 is mounted on each of the arms. 30 The discs are journaled upon pins which extend through the arms, all of which is usual and well-known in the art.

A water course 6 extends axially through the shank 1, and this course is bifurcated at the bottom 35 so that a stream of liquid is directed against each of the discs 5, thereby effectively cleaning the discs and washing all cuttings and débris therefrom.

The discs 5 may be formed with a plurality of 40 teeth or fingers 7 thereon, as shown in Figure 2, or the disc may be plain as shown in Figure 3. In order that the two discs 5 should rotate in unison as the bit is rotated in the bottom of the hole, we provide a plurality of inwardly extending 45 teeth or lugs 8 on each of the discs. These

lugs mesh when the discs are in position on the shank, and consequently will cause the other disc to also rotate. The lugs 8 are formed on the inner face of each of the discs and may be either integral with the disc, or may be formed 60 upon a separate ring which is suitably secured to the disc.

Having described our invention, we claim:

1. A rotary bit comprising a shank, discs rotatably mounted on the shank on axes disposed on opposite sides of the longitudinal axis of the bit and offset forwardly thereof in the direction of rotation of the bit, teeth extending from said discs, said teeth intermeshing whereby the discs are rotated in unison. 70

2. A rotary bit comprising a shank, a pair of arms depending from the shank, a disc rotatably mounted on each of the arms on axes disposed on opposite sides of the longitudinal axis of the bit and offset forwardly thereof in the direction 75 of rotation of the bit, teeth extending inwardly from each of the discs, said teeth intermeshing whereby the discs are rotated in unison.

3. A rotary bit comprising a shank, a pair of arms depending from the shank, a disc rotatably 80 mounted on each of the arms on axes disposed on opposite sides of the longitudinal axis of the bit and offset forwardly thereof in the direction of rotation of the bit, teeth extending inwardly from each of the discs, said teeth intermeshing 85 whereby the discs are rotated in unison, a plurality of radially extending fingers formed on each of the discs, said fingers engaging the ground to positively rotate said discs.

4. A rotary bit comprising a shank, a pair of arms on the shank, a disc cutter rotatably mounted on each of the arms on axes disposed on opposite sides of the longitudinal axis of the bit and offset forwardly thereof in the direction of rotation of the bit, engaging means on each of the 90 discs, the engaging means on each of the discs intermeshing whereby the discs are rotated in unison. 95
